CHIMNEY CONSTRUCTION

Robert W. McLaughlin, Jr., Bedford Village, N. Y.,
assignor to American Houses, Inc., New York,
N. Y., a corporation of Delaware

Application April 29, 1942, Serial No. 440,918

2 Claims.

(CL 98—46)

This invention relates to an improved chimney construction, and more particularly to a chimney construction in which the entire weight of the chimney is supported by the roof of the building. An object of the invention is to provide a chimney which may be readily and cheaply constructed, which may be assembled from prefabricated sections, which is light in weight, durable, safe and efficient, and which may, if desired, be disassembled and re-used in another building.

Other objects are to provide such a chimney of sections of steel coated, inside and outside, with vitreous enamel, to provide cheap, easily handled and rapidly assembled means for suspending a plurality of such sections, when assembled, from the roof of the building; to provide adequate ventilation for the attic of the building around the chimney; to provide means for protecting exposed sections of the chimney from contact with inflammable material; to provide such protective means as part of the chimney sections; to provide suitable means for giving access to the chimney for cleaning the same; to provide means for removing accumulated flue gas condensate from the chimney; and to provide means for so assembling the chimney sections that they may, if desired, be readily disassembled and used again in the construction of similar chimneys elsewhere.

Still other objects of the invention will in part be obvious and will in part appear hereinafter.

The invention accordingly comprises the features of construction, combination of elements, and arrangement of parts, which will be exemplified in the construction hereinafter set forth and the scope of the application of which will be indicated in the claims.

For a still further understanding of the invention, reference should be had to the following detailed description, taken in connection with the accompanying drawing, wherein:

Figure 1 is a view in vertical section of a portion of the roof and upper portion of the chimney of a dwelling equipped with a preferred embodiment of the invention;

Fig. 2 is a plan view of the top of the chimney and the adjacent roof of the structure shown in Fig. 1, with certain parts shown in dotted lines for clarity;

Fig. 3 is a view, partially in elevation and partially in vertical section, of the lower portion of the chimney;

Fig. 4 is a view in section along the line 4—4 of Fig. 1; and

Fig. 5 is a detail view in vertical section of a portion of a flue embodying the invention.

In the embodiment of the invention shown in the drawing, the chimney flue comprises either a single long flue section or preferably a plurality of relatively short and easily handled sections of standard length, for example three feet, bolted or otherwise fastened together to provide a continuous flue, and suspended, in a manner hereinafter described, from the roof of the building. All the intermediate flue sections 10 may, if desired, be identical. Each may comprise a substantially cylindrical steel tube 101 of suitable diameter, for example eight inches, having its inner and outer surfaces coated with a vitreous enamel layer 102. Each flue section should taper slightly so as to fit snugly into the upper end of the next lower section, as shown for example in Figs. 1 and 3. If desired, the lower outer portion of each flue section may be provided with an asbestos paper gasket 12 or other suitable means to insure an adequately tight fit between successive sections. Each section may be provided with lugs or other suitable bolt-receiving means 14 at each end thereof and preferably with a plurality, for example three, of such lugs at each end, evenly spaced around the outer surface of the section, to insure rapid and easy assembly of sections and adequate support between successive sections.

The uppermost and lowermost sections each differs slightly from the standard form of the intermediate flue sections. The uppermost flue section 16 is provided adjacent its upper edge with a plurality of apertures adapted to receive the rivets or bolts 18 by which it is connected to the depending flange 20 of a chimney cap element 22 as hereinafter described. It will be apparent, however, that the uppermost section 16 may, if desired, be identical with the intermediate sections 10, in which case the flange 20 would be provided with a plurality of lugs to provide means for mounting the flue section thereon. The lowermost chimney flue section 24 differs from the others in that it is provided with an elbow 26, adapted to receive a section of stove-pipe 28 leading from the furnace or heater 30. The section 24 is moreover provided at its lower end with a suitable cleanout cap 32 and with a pipe or drain 34. This last-mentioned element is of considerable importance. It is intended that it remain open, thus providing a conduit for the removal of flue gas condensate, which collects rather rapidly in the bottom of the

chimney and, unless promptly removed, may eat through the flue section.

Chimneys of the type described are adapted for use especially in inexpensive, prefabricated dwellings, in most of which the heater 30 is on the first floor, as no cellar is provided. Accordingly, 36 is intended to illustrate either the first floor, or cellar floor of the building, and drain 34 is shown as extending therethrough. It will be apparent, however, that drain 34 need not extend through a cellar floor if the presence of a small amount of condensate thereon is not objectionable.

Tests have established that a chimney made of flue sections such as have been described will not ordinarily become heated sufficiently to approach the ignition temperature of wood. For example, if stack gas temperatures not exceeding 835 degrees F. are maintained, the surface temperature of that portion of the chimney flue likely to pass through building construction will not exceed 250 degrees F., a temperature which provides an adequate safety margin even should there be actual contact between chimney flue and a portion of the frame structure of the dwelling. In order, however, to insure against such contact it is intended that where the chimney passes through a ceiling, floor or wall, means, preferably of poor heat conductivity, should be provided to insure the positioning of the chimney flue between, and not in contact with, adjacent studs or joists. Such means (not shown) may comprise straps to position the flue, or asbestos packing or the like. Moreover, where the chimney flue is likely to come in contact with inflammable material as, for example, in an attic, where such material may be placed against the flue, a modified form of flue section may be employed. Such a modified form of section is shown in Figs. 1 and 4. The basic flue section 10 may be provided, adjacent its upper and lower ends, with collars or rings 40 of heat insulating material, and these collars may support an outer cylindrical shell 42 of steel, for example. This shell may be spaced sufficiently from the flue section 10 to provide adequate protection and it may be vented as at 44 in several places to insure circulation of air therethrough.

In the embodiment of the invention shown in the drawing, the chimney flue such as has been described, or an equivalent thereof, is suspended from the roof of the building in the following manner. A supporting member 50, of any desired size and shape, but preferably rectangular in cross-section and made of sheet steel or other suitable material of such rigidity and strength as to perform adequately its intended functions, is nailed or otherwise affixed to two adjacent roof rafters 52, along the center lines thereof, as indicated at 54 in Fig. 2. As shown, the lower portion of the supporting member 50 extends laterally as a skirt 56, which serves as flashing. It is through this portion of the supporting member 50 that it is affixed to the rafters 52. The final roof covering, whether shingles or other material, may overlie the flashing 56, as shown diagrammatically in Fig. 1 at 58, while the flashing may rest directly on the rafters 52 or upon the boards used to rough-close the roof, if used, as shown in Figs. 1 and 2 at 60. If desired, the upper edge of the element 50 may be rolled over as shown most clearly in Fig. 1 at 62 to provide increased rigidity and strength.

The chimney cap element 22, also preferably of sheet steel or similar material, is preferably

of the same general cross-sectional shape as the member 50. The element 22 may, however, be somewhat longer than the member 50, although of approximately similar breadth. In addition to the central depending circular flange 20, to which the chimney flue is affixed, the member 22 is provided with a depending, rigid skirt or flange 64 to which the element 50 is affixed as at 66, by bolts, rivets or other suitable means along two opposite sides. As will be clearly apparent from Fig. 1, the upper edge of the supporting member 50 is spaced from the top of the chimney cap element 22. Moreover, the member 50 is of considerably larger internal over-all diameter than the diameter of flue section 16. It is thus apparent that surrounding the chimney flue there is provided a passage for ventilating the attic, thus preventing condensation therein even though the attic is not otherwise heated. The arrows 70 illustrate how heated air may flow from the attic, up along the chimney flue and out between the top of member 50 and chimney cap 22. The depending flange 64 is preferably of such length, as clearly shown in Fig. 1, as to provide protection from the weather for the ventilation passage just described. Where affixed to member 50, flange 64 should of course be against the outer face of member 50.

Suitable standard means (not shown) may be employed to protect the flue opening in the cap element 22 from rain, snow and the like.

As has been mentioned, a chimney construction embodying the present invention is admirably adapted for use in inexpensive dwellings of the prefabricated and demountable type. Such a chimney is itself demountable. It may be salvaged entirely, should the dwelling in which it is in use be dismantled. The individual flue sections may be re-used to construct other chimneys, or the entire chimney structure may be reassembled in a new location. Furthermore, in the initial construction and in each re-use of the flue sections, the assembly is a "dry" job. No masonry is required and the building cost is thus substantially reduced. The method of suspending the chimney flue from the roof, as herein described, has been found to be greatly preferred over a construction in which the chimney is supported from the bottom. In fact, with chimney flues of the character described, the overhead suspension of the present invention has been found practically a necessity.

Since certain changes may be made in the above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all the generic and specific features of the invention herein described, and all statements of the scope of the invention which, as a matter of language, might be said to fall therebetween.

What is claimed is:

1. In a building construction of the character described, in combination, a chimney comprising a plurality of demountable flue sections, means for fastening said sections together in substantially end-to-end relation, means, including spaced rafters, providing a roof for said building, a chimney-supporting member, rectangular in cross-section, affixed to a plurality

of said rafters and a chimney cap element affixed to the uppermost flue section and to two opposite walls of said supporting member whereby said chimney is entirely suspended from said roof, said cap element having a downwardly depending flange spaced from and positioned outwardly of the two walls of said supporting member to which said cap is not affixed, whereby there is provided a ventilating conduit, shielded from the weather, between said supporting member and the uppermost flue section.

2. In a building construction of the character described, in combination, a chimney comprising a plurality of demountable flue sections, each of said sections tapering gradually in diameter from a maximum diameter at its upper end to a minimum diameter at its lower end, means for fastening said sections together in substantially

end-to-end relation with the lower end of each section positioned within the upper end of the next adjacent lower section, means, including spaced rafters, providing a roof for said building, a chimney-supporting member, rectangular in cross-section, affixed to a plurality of said rafters and a chimney cap element affixed to the uppermost flue section and to two opposite walls of said supporting member whereby said chimney is entirely suspended from said roof, said cap element having a downwardly depending flange spaced from and positioned outwardly of the two walls of said supporting member to which said cap is not affixed, whereby there is provided a ventilating conduit, shielded from the weather, between said supporting member and the uppermost flue section.
